UNITED STATES PATENT OFFICE

JULIUS A. FISCHER, OF PHILADELPHIA, PENNSYLVANIA

TONE ARM

Application filed July 20, 1928. Serial No. 294,270.

This invention relates to sound reproducers, but more particularly to the attachment between the sound box and the tone arm, and the invention has for its object to provide, in 5 a manner as hereinafter set forth, a new, improved, durable, adjustable and efficient sectional sound conducting attachment between the sound box and the tone arm and with said attachment including novel stop means for 10 arresting the shifting of the sections thereof with relation to each other.

With the above and other objects in view, the invention consists of the novel construction, arrangement and combination of parts 15 as hereinafter more specifically described, and as illustrated in the accompanying drawings, wherein like numerals are employed to designate like parts throughout the same, and in which,

20 Figure 1 is a plan of an attachment in accordance with this invention, attached to a sound box shown in operative position.

Figure 2 is a section taken on line 2—2 Figure 1.

25 Figure 3 is a fragmentary front elevation of the structure shown in Figure 1.

Figure 4 is a section taken on line 4—4 Figure 2.

30 Figure 5 is a section taken on line 5—5 Figure 2.

Figure 6 is a fragmentary perspective view of the goose neck.

35 Figure 7 is a perspective view of the elbow which connects the goose neck with the tone arm coupling.

In the drawings wherein for the purpose 40 of illustration is shown an embodiment of my invention, the numeral 1 designates a sound box, which may be of any well known construction, and forms no part of this invention. Carried by the sound box 1 is a 45 goose neck indicated generally at 2, which is connected by one of its ends 3 with the sound box, and gradually increases in diameter from such end 3 to the opposite end 4. The 50 goose neck is provided with a curved portion 5, substantially in the form of a semi-circle, said curved portion being located between the transverse median of the length of 55 the goose neck 2 and the smaller end 3 there-

of, so that the larger end 4 extends forwardly beyond the smaller end 3.

Spaced from the end edge 6 of the goose neck 2, as more clearly shown in Figure 6, is 55 a slot 7, which extends circumferentially of the goose neck, for substantially one-half the circumference thereof. Adapted for connection with the end 4 of the goose neck 2, is an elbow 8, which is formed at one end with an enlarged outwardly offset portion 9, thereby forming therein an annular shoulder 10. The width of the shoulder 10 is equal to the thickness of the wall 2. The inner diameter of the enlarged portion 9 is slightly greater than the outer diameter of the end 4 of the 65 goose neck 2, in order that the end 4 may be loosely received within the enlarged portion 9.

When the elbow 8 and the goose neck 2 are 70 in assembled relation, the edge 6 of the goose neck 2 is in abutment with the shoulder 10, and an uninterrupted passage is provided between the two parts. Threaded through the wall of the enlarged portion 9 is a set screw 11, which extends into the slot 7 and prevents 75 longitudinal movement between the goose neck 2 and the elbow 8. Relative rotary movement is provided between the goose neck 2 and the elbow 8, for a circumferential distance equal to the length of the slot 7. At the termini of this rotary movement, the set screw 80 11 abuts against the respective ends of the slot 7.

The elbow 8 is formed with the ends thereof at right angles to each other, and the end 12 opposite to the end 9 is formed with a reduced 85 externally threaded neck 12, and an external annular shoulder 13. Projecting from the edge 14 of the neck 12, and extending lengthwise of said neck, is a pair of studs 15, which are offset relative to the diameter of the neck 90 12.

A tone arm coupling 16 is connected with the elbow 8, by means of the internal threads 17 which engage the external threads of the neck 12. The end of the tone arm coupling 95 16, which is in engagement with the elbow 8 is enlarged and formed with an angular recess to provide a shoulder 18 and a lip 19. When the tone arm coupling 16 and the elbow 8 are in assembled relation, the shoul- 100

ders 18 and 13 are in abutment and the inner surface of the lip 19 is in engagement with the outer surface of the elbow 8. A set screw 20 extends through the wall of the tone arm 16, and projects between the studs 15 projecting from the end of the neck 12. Limited rotary movement is provided between the tone arm 16 and the elbow 8, for a circumferential distance equal to the circumferential distance between the studs 15. The opposite end of the tone arm coupling is offset substantially at a right angle, and is provided with a transversely extending bore 21, for connection with a tone arm not shown.

It will be readily seen that my improved attachment provides for free movement of the sound box, in both a vertical and a horizontal plane, without the necessity of any movement of the tone arm. Due to the threaded connection between the tone arm coupling 16 and elbow 8, and to the removable set screw 20, the foregoing movement of the sound box may be had regardless of the angular relation between the end portion 4 of the goose neck 2 and the tone arm with which the tone arm coupling 16 is adapted to be connected. By this arrangement the tone arm may be extended from any direction desired.

It is to be understood that the embodiment of the invention herewith shown and described is to be taken as a preferred example of the same, and that various changes in the size, shape and arrangement of parts may be resorted to without departing from the spirit of the invention or the scope of the appended claims.

What I claim is:

1. An attachment for sound boxes comprising, a goose neck adapted to be connected with a sound box, an elbow rotatably connected with the goose neck, means for limiting the rotary movement between the elbow and goose neck, a tone arm coupling adapted to be connected with a tone arm, and means connecting the tone arm coupling with the elbow to permit a limited rotary movement therebetween, said last named means coacting with the connection between the elbow and goose neck to provide for horizontal and vertical movements of the sound box regardless of the angular relation of the tone arm with respect to the goose neck.

2. An attachment for sound boxes comprising, a goose neck adapted to be connected with a sound box, an elbow rotatably connected with the goose neck, means for limiting the rotary movement between the elbow and goose neck, a tone arm coupling adapted to be connected with a tone arm, and means connecting the tone arm coupling with the elbow to permit a limited rotary movement therebetween, said last named means coacting with the connection between the elbow and goose neck to provide for horizontal and vertical

movements of the sound box regardless of the angular relation of the tone arm with respect to the goose neck, said last named means including external threads adjacent one end of the elbow, a pair of spaced studs projecting from said end, internal threads on the tone arm coupling for engagement with said external threads, and a removable set screw extending through the wall of the tone arm coupling and projecting between said studs.

3. An attachment for sound boxes comprising, a goose neck adapted to be connected with a sound box, an elbow rotatably connected with the goose neck, means for limiting the rotary movement between the elbow and goose neck, a tone arm coupling adapted to be connected with a tone arm, and means connecting the tone arm coupling with the elbow to permit a limited rotary movement therebetween, said last named means coacting with the connection between the elbow and goose neck to provide for horizontal and vertical movements of the sound box regardless of the angular relation of the tone arm with respect to the goose neck, said last named means including external threads adjacent one end of the elbow, a pair of spaced studs projecting from said end, internal threads on the tone arm coupling for engagement with said external threads, and a removable set screw extending through the wall of the tone arm coupling and projecting between said studs, said tone arm coupling being formed with an internal recess adjacent said internal threads, said elbow having an external shoulder adjacent said external threads for engagement in said recess.

In testimony whereof, I affix my signature hereto.

JULIUS A. FISCHER.
